OUTSERT ATTACHMENT

Thormod Jensen, Laurelton, N. Y., assignor to
 American Machine & Foundry Company, a
 corporation of New Jersey

Application March 18, 1937, Serial No. 131,651

1 Claim. (Cl. 154—37)

This invention relates to improvements in wrapping machines, more particularly to an outsert attachment acting to secure a label band to the main wrapper web by application of heat. 5 Heretofore various principles were adopted for attaching the label band to the wrapping material, among which was that of melting the wax coating of the label band prior to its application to the wrapping material. However in the latter type the distance between the heating zone and the roll of wrapping material varied with the diameter of the roll during depletion thereof, wherefore the heater members were necessarily held at an excessive temperature requisite 10 for maintaining the fused condition of the band throughout these varying distances, which burned the label band when the heater was left in contact therewith during machine stoppage unless removed manually or automatically. According- 15 ly, the main object of the invention is to provide heater mechanism whereby a constant distance is maintained between the heating zone and the point of application of the fused band to wrapping material, so that the heater may be kept 20 at a predetermined temperature which will sufficiently fuse the thermoplastic coating of the band without scorching the same when left in contact therewith during machine stoppage.

To this end there is provided a movable frame 30 or support which carries the heater and a roller which rests on the periphery of the roll of wrapping material to press the fused band into adhering relation with the portion of the wrapping material being drawn off the roll. In the course 35 of its operation the wax or other thermoplastic material coating of the band would accumulate on the surface of this roller, and it is a further object of the invention to remove the accumulated wax in a novel and efficacious manner. For 40 this purpose the heater shoe over which the label band is guided on its way to the wrapping material, extends into proximity to the sealing roller in order to melt the wax thereon.

Since the operation of the wrapping machine 45 is periodic the feeding of the wrapping material is necessarily intermittent and would result in breakage of the label band when the latter assumes an inclined position between the band reel and the heater shoe due to lowering of the 50 same through depletion of the wrapping material roll. To avoid such breakage is still another object of the invention, and with this in mind there is provided a roller aligned with the band reel and over which the band is guided on its 55 way to the heater shoe. The inertia of the

band reel during its rotation while the band is being drawn off causes overrunning of the reel and thereby creates slack in the stretch between the reel and guide roller, when the feeding of the wrapper material and band is interrupted. 5 This slack is sufficient to prevent breakage of the label when its feeding is resumed. With these and other objects not specifically mentioned in view, the invention consists in certain constructions and combinations hereinafter fully described and then set forth in the appended 10 claim.

In the accompanying drawing which forms a part of this specification and in which like characters of reference indicate the same or like 15 parts:

Fig. 1 is a plan view of the outsert attachment; and

Fig. 2 is a side view of the same.

Referring to the drawing, the band reel R 20 on shaft 10 is shown suspended from rods 11 and 12 of the machine by hangers 13 and 14. The heater unit may consist of a resistance heater 15 attached to the heater shoe 16 carried by arms 17 and 18 and connected to an electrical supply circuit by wires passing through a switch box (not shown) located at some convenient point of the machine. When the material used for the label band is waxed paper, a temperature in the neighborhood of 300 degrees 30 F. is desirable and a heater of 150 watt capacity has been found satisfactory.

Arms 17 and 18 are loosely mounted on a shaft 19 fastened in brackets 20 and 21 mounted on the frame 22 of the wrapping machine. Said 35 arms are united by tie rods 23 and 24 to form a frame wherein is supported a roller 25 adapted to engage and press the heated label band B on to the roll of wrapping material R'.

The web of wrapping material W may be drawn 40 from the roll R' in any suitable manner. If desired, the present wrapper bander may be used in conjunction with the wrapping mechanism disclosed in Patent No. 1,926,245, granted September 12, 1933, on the application of F. R. Schmitt. It 45 may be noted that the present wrapper bander differs from that shown in the patent just mentioned in that the present heater unit for the label band is located in advance of the roll of wrapping material whereby the band B is heat 50 sealed to the wrapping material W immediately as they contact on the roll R'.

The label band B is drawn over the rod 24' and then threaded between the rod 24' and heater shoe 16, and thence under roller 25 on to the 55

wrapping material roll R' where the roller 25 presses the heated band into adhering relation with the web W. The function of the roller 24 is to maintain the label band in contact with the heater shoe during its passage thereover. As mentioned above, the formation of slack in the horizontal stretch of the band B between the reel R and roller 24' prevents breakage when the feeding of the wrapping material and band is resumed. If the roller 24' were omitted the stretch between the heater shoe and the band reel would assume an inclined position when the diameter of the roll of wrapping material diminished, and would be broken due to its inclined relation to the heater shoe when feeding was resumed. The banded web of wrapping material is carried along over the various rollers 26, 27, 28 and 29 into the wrapping machine.

The heater shoe 16 is placed close enough to the roller 25 to melt and thus free it of any possible accumulation of wax. In practice a clearance of one ten thousandth of an inch has been found sufficient. Since the arms 17 and 18 pivot on shaft 19, the sealer roller 25 rests on the wrapper material roll R' and continues engaging the same as the same diminishes in diameter. For convenience in replacing a depleted reel of wrapping material roll by a new roll, the frame consisting of arms 17 and 18 may be lifted up and held in its up-position by a latch arm 30 engaging the tie rod 23, arm 30 being pivotally mounted on a stud carried by a member 31 attached to frame 22.

What is claimed is:

In an apparatus of the class described for sealing together webs of sheet material, at least one of which has a heat-responsive sealing component, a supporting structure including an upright frame member, rods extending substantially horizontally therefrom, a band web reel supported by hangers depending from said rods at a fixed point relatively remote from said frame member, a wrapping material roll journaled in fixed position between said band web roll and frame member, directly beneath said rods, a swinging bracket associated pivotally with said frame member and having at its free end a pressure roller in position gravity biased into contact with the uppermost arc of said wrapping material roll at all times as the same is depleted, independently of said band web roll, a sealing element also on said free end of the pivot arm and means to heat said sealing element suitably to render said heat-responsive component effective for sealing purposes and also to heat said pressure roller adequately to prevent accumulation thereon of said heat-responsive component, and a direction device mounted upon said webs to lead said band web downward substantially in an extension of the radius of said wrapping material roll, substantially in the manner and for the purpose set forth.
